UNITED STATES PATENT OFFICE.

SAMUEL B. SCHENCK, OF WILKINSBURG, PENNSYLVANIA, ASSIGNOR TO WESTINGHOUSE ELECTRIC & MANUFACTURING COMPANY, A CORPORATION OF PENNSYLVANIA.

BUS-LINE CONNECTER.

Application filed June 5, 1922. Serial No. 566,196.

My invention relates to bus-line connectors for trains, more especially to a device for connecting up the power line between cars in an electrical railway train.

5 It is among the objects of this invention to provide an improved type of connector which utilizes the power drawn therethrough to securely lock the connecting parts and to provide an efficient electrical connection 10 therebetween.

It is a further object of this invention to provide a device of the above-designated type which shall be of simple compact structure, inexpensive to manufacture and adapted for 15 application to general bus-line connectors on railway cars.

Various means of securing bus-line connectors have been devised and generally comprise mechanical latching devices for securing 20 the jumper heads in their sockets. Frequently, trouble occurs from the connector or jumper head coming loose in its socket and, when power is drawn through the contacts, the loose joint causes arcing and severe 25 burning of the contact members.

My present invention is designed to provide a magnetic device utilizing the power drawn through the connector to attract the jumper head and securely hold it in its receptacle or socket, thereby preventing breaking 30 of the contact therebetween.

In the accompanying drawing constituting a part hereof and in which like reference characters designate like parts,

35 Figure 1 is a cross-sectional view of a bus-line connector embodying the principles of my invention;

Fig. 2 is a cross-sectional view, partially in elevation, of the device shown in Fig. 1, with 40 the jumper head or plunger separated from the socket connection.

As shown in the Fig. 1, the device consists of a hollow cylinder 1 provided with a mounting bracket 2 which is secured to the 45 end of a railway car in alignment with a similar device on another car, their respective positions being located from the coupler heads. One end of the cylinder 1 is provided with a flange 3 on which a disc shaped 50 cover 4 is mounted and secured by bolts 5. The cylinder 1 is adapted to receive a jumper head or plunger 6 having an extension 7 on one end thereof which is provided with a constricted opening 8 adapted to receive a

cable 9. The plunger 6 is further provided 55 with an enlarged opening 10 communicating with a recess 11 to provide a seat for the flange 12 of a terminal bushing 13 which is disposed therein. A terminal plug 14, secured to the cable 9, is disposed in the bushing 13 and constitutes one side of the bus-line connection.

The jumper head or plunger 6 is insulated from the cylinder 1 by an insulating bushing 15 of suitable, preferably fibrous, material, 65 and a hardened binder of the well-known phenolic-condensation-product type which is secured thereto in a suitable manner, as by a press fit. An iron core 16, having a central opening 17 extending therethrough, is 70 mounted on an insulating base 18 which is provided with a central opening 19, and an insulating spacer 20 having an opening 21 is disposed on the other end thereof.

Another iron block 22 is secured between 75 the insulating base 18 and cover 4 in alignment with the core member 16, and a conductor 23 having an enlarged end 24 is disposed in the contact terminal 14 and is projected through the openings 19 and 21 of the 80 insulators 18 and 20, respectively. The other end of the conductor 23 is wound around the core 16 to form a coil 25 and is then inserted through the insulating base 18 and an opening 26 provided in the cover 4 to establish 85 the other bus-line connection.

My device operates briefly as follows: The jumper head 6 is plugged into the cylinder 1 until it rests against the insulating spacer 20, causing the terminal 24 of the conductor 23 to make contact with the bus-line terminal 13, as illustrated in the Fig. 1. When the circuit is energized, the current will flow through the coil 25, causing a magnetic field to be established in the iron core 90 16, block 22, cover 4 a portion of the cylinder 1 and the contacting end of the plunger 6, thus causing strong magnetic attraction 95 on the jumper head to hold it firmly against the spacer 20.

The strength of the magnet varies with the amount of current passing through the conductor so that, when the mechanism is subjected to the greatest strain, the magnet 100 will be at its greatest capacity.

It will be readily understood from the above description of my invention that a connector device formed in accordance there-

with provides a mechanically simple and electrically efficient connection which is easy to manipulate and may be readily mounted upon any accessible part of the car unit.

5 Although I have described a specific embodiment of my invention, it will be obvious to those skilled in the art that various modifications may be made in the details of construction. For instance, the jumper head 10 or plunger may be of any suitable shape designed to facilitate forming of the bus-line connection and the arrangement of the contact terminal and the magnet may be of a suitable design to accommodate the size 15 of wire or cable mounted thereon and to obtain the capacity required. The general design of the housing and mounting bracket may be modified to adapt them for specific 20 application. These and other changes may be made in the details of construction without departing from the principles herein set forth.

I claim as my invention:

1. A bus-line connector comprising a hollow cylinder having a mounting bracket 25 formed integrally therewith and adapted to receive a plunger having an insulating bushing disposed therearound, a terminal bushing adapted to secure a bus-line on one end 30 and a contact member on the other centrally disposed in said plunger and magnetic means for securing said plunger in said cylinder, said means comprising a solenoid secured to said cylinder and insulated therefrom and 35 having one of its leads secured in said terminal bushing.

2. A bus-line connector comprising a hol-

low cylinder provided with a mounting bracket which is adapted to receive a plunger, an insulating bushing disposed around 40 said plunger, a terminal bushing centrally disposed therein, a bus-line terminal provided with a recess which is adapted to receive a terminal head secured in said bushing, an iron core centrally disposed in one end of 45 said cylinder and secured therein by an insulating spacing disc, a coil wound on said core, one end of which is disposed in said terminal and an insulating spacer disposed between said plunger and core. 50

3. A bus-line connector comprising a hollow body member, a contact member mounted in said body member, a plunger, a second contact member attached to the plunger and adapted to co-operate with the 55 first named contact member, and an electromagnet mounted in the body member and adapted to secure the plunger in the body member.

4. A bus-line connector comprising a hollow body member, a contact member mounted in said body member, a plunger, a second contact member attached to the plunger and adapted to co-operate with the 60 first named contact member, and an electromagnet mounted in the body member and adapted to secure the plunger in the body member, said electromagnet having one of 65 its leads secured to said first named contact member. 70

In testimony whereof, I have hereunto subscribed my name this 22nd day of May, 1922.

SAMUEL B. SCHENCK
